ALARM SIGNAL STATION

Leo L. Verkuil, Norwalk, Conn., assignor to Edwards Company, Inc., Norwalk, Conn., a corporation of New York

Application April 13, 1951, Serial No. 220,868

20 Claims. (Cl. 200—52)

1

This invention relates to signal stations, such as a fire or other alarm signalling station.

One of the objects of this invention is to provide a compact, inexpensive, and reliable signalling station that can be manufactured and assembled with facility and mounted or installed in a simple manner. Another object is to provide a manually-actuatable signalling station that will be neat in appearance, simple to operate, and capable of embodying therein a breakable element, like a glass member, as a deterrent, without detracting from compactness of construction and ease of operation. Another object is to provide an alarm signalling station having a breakable element therein, in which moldable plastics may be structurally employed and the breaking mechanism so constructed that the substantial force necessary to break the breakable element, such as a glass member, may be dependably exerted without structural impairment of the molded plastic structure.

Another object is to provide a so-called break-glass alarm signalling station in which the breakable element is mounted and replaceable in a simple and practical manner and in which provision is made for selectable legend display according to the particular use to which the station is to be put, such as, for example, for "Fire" or "Emergency," etc. Another object is to provide a signal station of the above-mentioned type in which switching mechanism and manual actuator may be assembled to the apparatus in a simple, speedy, and inexpensive way. Another object is to simplify, in an inexpensive manner, problems of electrical insulation met with in signal stations of this type and to achieve electrical safety in a simple and dependable manner. Another object is, in general, to provide an improved alarm signalling station of the above-mentioned nature.

Other objects will be in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawings, in which similar reference characters refer to similar parts throughout the several views—

Figure 1 is a front elevation of the signalling station as it appears ready for installation;

Figure 2 is a rear elevation, as seen from the rear in Figure 1;

Figure 3 is a horizontal cross-section as seen

2

along the line 3—3 of Figure 1 and of Figure 2;

Figure 4 is a horizontal cross-section as seen along the line 4—4 of Figure 1 and of Figure 2;

Figure 5 is a horizontal cross-section as seen along the line 5—5 of Figure 1 and of Figure 2;

Figure 6 is a central vertical sectional view as seen along the line 6—6 of Figure 1 and of Figure 2, but also showing one form of mounting of the signalling station in use;

Figure 7 is a fragmentary and enlarged rear elevation, being an enlargement of a portion of Figure 2 to show more clearly the support for a pivot pin, and

Figure 8 is a horizontal sectional view along the line 8—8 of Figure 7.

Referring first to Figures 1, 2, and 6, the signalling station comprises a support, generally indicated by the reference character 10, comprising a front wall 11, illustratively rectangular in outline, provided with a peripheral rearwardly extending flange 12 whose continuous peripheral edge can rest flatwise against the face of a suitable support, usually a wall W, as indicated in Figure 6. At suitably distributed points, illustratively along the center line and near the top and bottom, the support 10 is provided with counterbored holes or slots 13—13 for the reception of securing means, such as screws 14—14 (Figure 6) which are screwed into the supporting wall or threaded into suitable threaded holes in lugs or ears or other parts associated with any suitable form or shape of outlet or conduit box 15 (Figure 6) which may be set into a recess 17 in the wall W, as indicated in Figure 6. In the latter case, the expanse of the rearward flange 12 is greater than that of the recess 17 so that the flange engages the wall surface and holds the front wall 11 of the support 10 parallel to the wall, even though the screw hole bearing parts associated with the outlet box are out of alignment with the face of the wall W; the horizontal direction of the slots 13 (Figure 1) permits adjustment of the support 10 so that it is plumb. Preferably the screw holes 13—13 extend through

20 bosses 16—16 (Figure 6) that are integrally formed in the support 10, the bosses being tapered and terminating in the same plane with that of the edges of the peripheral flange 12. The support 10 may thus be tightly secured against the flat surface of a wall or the like. If desired, shims or washers may be interposed between the bosses 16, 16 and the threaded lugs or ears of the outlet box 15 in case of substantial misalignment of the latter relative to the wall W.

reference character 20, being integrally formed therewith and, in the illustrative embodiment, having a greater horizontal dimension than its vertical dimension, as better appears in Figure 1; this portion comprises a back wall 20^a whose rear face preferably does not project beyond the plane of the edges of the peripheral flange 12 (see Figures 3 and 6) joined to the front wall 11 by opposed side walls 20^b and 20^c and top and bottom walls 20^e and 20^f. Opposed end walls 20^b and 20^c are rearwardly convergent, as are also opposed top and bottom walls 20^e and 20^f (Figures 3 and 6), and, being of substantially uniform thickness, the spaces which they define from either front or rear are tapered and thus facilitate drawing or separation of the mold parts where the support 10 is cast or is made of molded plastic material. On the front face of back wall 20^a, in good-sized lettering, formed therein in relief, as indicated at 21 in Figures 3 and 6, appears the legend "Pull," being a visual instruction as to how to operate a manual actuator, generally indicated by the reference character 22, and a part of which is related to the pocket-forming portion 20 in a manner later described.

In another portion of the front wall 11, the latter is depressed or displaced to form a back wall 23 (Figures 4, 6, and 2) that is rectangular in shape and is peripherally surrounded by a rectangular ledge or rabbet 24. I provide a frangible element, preferably in the form of a rectangular plate of glass 25 (Figures 1, 4, and 6), which is dimensioned to just about fit against the front side of the back wall 23, being of a thickness just about equal to or less than the height of the ledge 24 that surrounds the back wall 23 so that the small plate or sheet of glass 25 is peripherally surrounded by the rectangular ledge 24 and its front face, being the upper face as viewed in Figure 4, falls just about in the plane of the front face of the ledge or rabbet 24. The glass element 25, thus easily and simply inserted into its seat against the rectangular back wall 23, is held against removal or against falling out of its seat by an open rectangular frame, generally indicated by the reference character 27, shaped in outline substantially as shown in Figure 1. It may also be made of molded plastic material. It rests flatwise against the ledge 24 (see Figure 4), neatly fitting into the above-mentioned rabbet of which the ledge 24 forms a part. It has upper and lower horizontal portions 27^a and 27^b whose vertical dimensions, as seen in Figure 1, are such that the vertical dimension of the opening 27^c in the frame 27 is greater than the vertical dimension of the glass plate 25, and it has vertical side portions 27^e and 27^f which are wider than the ledge 24 against which they rest and hence they overlap the left-hand and right-hand end portions of the glass plate 25, as is clearly shown in Figures 1 and 4. Screws 28-28 (Figures 1 and 4) pass through holes in the vertical side portions 27^e and 27^f of the frame 27 and are threaded into rearwardly projecting rectangular bosses 29 and 30 (Figures 4 and 2), integrally formed with the front wall 11. As is better shown in Figure 4, the screws 28-28 thus secure the glass-holding frame ends 27^e and 27^f tightly against the ledge 24 but closely adjacent those frame portions that overlap the horizontal ends of the glass plate 25; the latter is thus not only securely held in place, but is dependably anchored at its ends against the breaking stress applied to it near the mid-point of its length by the anvil 31 formed on the manual actuator 22 (see Figure 6) and extending through

a hole 23^a in the back wall 23 against which the glass plate 25 rests.

Frame 27 bears a suitable legend, such as "Fire," as indicated at 32 (Figure 1), across one of the horizontal portions of the frame, preferably the upper one 27^a. The frame 27 is readily detachable by removing the screws 28, 28, so that the broken glass 25 can be replaced. I make suitable provision for preventing reassembly of the frame 27 to the support 10 in inverted or upside-down position, and such provision I preferably carry out in a manner also to permit selective display of either of two legends, of which the one may be the word "Fire," as above noted, and the other may be the word "Emergency." Accordingly, the legend "Fire" appears on the front face of the upper cross-part 27^a, in relief, as shown in Figures 4 and 6, and on the back face of the upper cross-part 27^a of the frame 27 appears the word "Emergency," with its letters also in relief, as indicated at 33 in Figure 6. The upper horizontal part of the ledge 24 I provide with a rectangular recess 34, as shown in cross-section in Figure 6 and in broken lines in Figure 1. Recess 34 is deep enough to accommodate the thickness of the relief lettering 32 and 33 and is of a length and breadth to let the projecting letterings of the two words "Fire" and "Emergency" project into it.

Accordingly, the glass holding frame 27 can be attached in either of two positions for holding the glass plate in place, in one of which the relief lettering "Fire" faces toward the front and the relief lettering "Emergency" faces to the rear, is not visible, and is snugly accommodated in the recess 34 in the ledge 24, and in the other position these relationships of the two words are reversed. The relief lettering in each case prevents attaching the frame 27 in upside-down position, for in such case the relief lettering on the inside face of the frame 27 has no recess in the lower horizontal reach of the ledge 24 into which it can enter, it is impossible to align the frame 27 flush with the front face of the wall 11, and this effect is aided by the different widths of the upper and lower horizontal portions 27^a and 27^b of the frame 27.

The manual actuator 22 is preferably in the form of a lever of appropriate length and relationship to the frangible or glass part 25 to provide substantial force multiplication for breaking the member 25. As is better shown in Figure 6, it has a straight portion 22^a that extends vertically across the back of the back wall 23 of the seat for the glass element 25 and an upper U-shaped portion 22^b that forms a finger-piece and bridges across the pocket or well 20 formed by the rearwardly bulging portions of the front wall 11, as above described. The upper and lower walls 20^e and 20^f of the well have slots 35 and 36 through which the finger-piece portion 22^b of the lever 22 extends. At its lower end, the lever 22 pivots about a horizontal axis formed by a pivot pin 37 so that lever 22 can swing toward or away from the front wall 11 of the support 10. The anvil 31, as shown in Figures 6 and 1, projects forwardly and is positioned close to the pivot pin 37 so that it has a small or short lever arm compared to the very much longer lever arm of the finger-piece 22^b, the ratio of the latter to the former being the measure by which a relatively small pull on the finger-piece 22^b is multiplied into a larger and substantial force to break the glass 25.

The lever 22 is normally biased to hold the anvil 31 in engagement with the frangible ele-

ment 25, as shown in Figure 6, the element 25 serving to limit the outward swing of lever 22 and thereby position the vertical reach of the finger-piece 22^b just beyond the plane of the front face of the front wall 11, giving the finger-piece sufficient visibility and, in conjunction with the well 20 and the instruction "Pull," inviting the insertion of one or two fingers behind the finger-piece 22^b and crosswise into the well 20.

To bias the lever 22 as above described, I employ a suitable spring which I preferably construct to form a part of a signalling switch that is connected into the signalling circuit that is to be activated by the alarm station. A preferred form of construction is shown in Figures 2 and 4 and comprises two switch elements 41 and 42 made of any suitable sheet metal and appropriately shaped and dimensioned for ease of manufacture, as by a punch press operation. Thus the switch part 42 projects laterally from a base portion 43 (Figure 2) which is elongated to rest flatwise against the rectangular boss 39 to which it is secured by screws 44 threaded into the boss; one of the screws can serve as a connector for one of the circuit conductors, as indicated in Figure 2, or, if desired, the portion 43 can be provided with a slotted or apertured tab-like end with which the conductor is engaged and to which it is preferably soldered. Switch contact part 42 extends crosswise toward the lever 22 and terminates short of it; as shown in Figure 4, part 42 can be bent for appropriate adjustment in relation to the coacting switch part 41, the shaping of the various parts providing ample space for such bending.

The switch part 41 also extends laterally from a flat base part 45 which is secured to the flat boss 29 in any suitable way, as by the screws 46; circuit conductors may be connected thereto, as by one of the screws 46 or by a tab end the same as above described for the other switch contact part.

The switch arm 41 extends crosswise and is of sufficient length to reach over and beyond the lever 22, and it may be bent, as shown in Figure 4, providing also an edge directed toward the stationary contact part 42 and against which it can make rubbing contact. The switch arm 41 is made of a suitably springy sheet metal, such as brass or Phosphor bronze, and it bears against the lever 22 to bias it, as above described.

Since the lever 22 is preferably made of metal, I provide for a non-conductive engagement between the switch part 41 and lever 22, as by an interposed small sheet or stamping 47 (Figures 2 and 4) of suitable insulating material, such as fiber or hard rubber. The sheet 47 is stamped out somewhat in the shape of the letter H (Figure 2), and the rear edge of the switch part 22^a of lever 22 is cut away somewhat in the form of a dovetailed groove or slot, as is better shown in Figure 6. The insulating plate 41 is securely held assembled to the lever 22 by engaging the upper and lower edges of the cross bar of its letter H form beneath the overhanging upper and lower edges of the dovetailed cross slot 22^a. In assembly, this is easily done by slightly flexing the insulating sheet 47.

As above noted, the support 10 is preferably made of a material that can be molded and, as thus far described, its configuration lends itself well for molding with companion molds or mold parts that are relatively separable in directions

from front to rear, as viewed in Figure 1, or from left to right, as viewed in Figure 6, thus also making use of the various converging or tapering wall surfaces earlier above described. 5 However, with companion mold parts so separable, complications and difficulties are introduced if it is attempted to also mold a hole or holes to receive the lever pivot pin 37 whose axis extends transversely to the direction in 10 which the companion mold parts have to be separated. On the other hand, drilling such a hole involves additional operations and complications, and also expense. These difficulties and obstacles I overcome while retaining the advantages of the above-described kind of molding operation, which is particularly desirable when the support 10 is to be made of any suitable moldable and curable plastic material.

The transverse pivot pin 37 is preferably positioned to the rear as viewed in Figure 1, and to the right as viewed in Figure 6, of the lower horizontal part of the ledge 24 against which the glass-holding frame 27 rests, so that the lower horizontal part 27^b of frame 27 can normally close over and cover up the front end of a tapered recess 50 of generally rectangular cross-section, as is better shown in Figures 5, 6, 7, and 8, the wall 23 being appropriately increased in thickness rearwardly to form in effect a boss 23^b (Figures 7 and 8) which merges into the adjacent boss 16 that is provided for the screw slot 13, the boss 16 thereby strengthening and reinforcing the boss 23^b at the inner end of which are formed the parts that support the pivot pin 37 and provide a good internally-cylindrical seat or support therefor.

These support or bearing portions for the pivot pin comprise a number of parts spaced along the axis of the pin 37, certain of them, 51 and 52, providing a partial pin seat 53 of 180 degrees facing toward the front end of the recess 50 and the others, 54 and 55, providing a partial seat 56, 57 of 180 degrees for the pin facing to the rear, as is better shown in Figures 7 and 8. Parts 51 and 52 are spaced apart (Figures 7 and 8) to provide between them a slot 58 in which to receive the lever 22, as shown in Figure 5, that end of the lever being brought into the slot 58 after the upper end of the lever, as seen in Figure 6, is snaked through and into the slots 36 and 35 of the finger well 20. This operation of assembly is simple and quickly accomplished because, as the glass-breaking handle 31 is entered into the hole 23^a in the wall 23, which it can do only by having the lower end of the lever 22 enter into the slot 58, the pivot pin hole in the lever 22 is thereby practically aligned with the complementary axially-spaced half-seats 56, 53, 53, and 57, the latter and the hole in the lever being of the same radius; pivot pin 37 is then easily inserted from the rear of the support and into the position better shown in Figure 5. The pin 37 may be held against axial displacement by any suitable means; for example, one of its end portions may be tapered or of slightly enlarged diameter or burred, or otherwise enlarged or deformed so as to cause it to bind in the two adjacent half-seats at that end of the pin, for example, the complementary half-seats formed by the parts 52 and 55.

The lever 22 is thus given a secure and strong pivotal support at its lower end, backed up and reinforced by the merging of the spaced complementary parts into the substantial boss 16 for the screw slot 13. Moreover, drilling of a seat

for the pin 37 need not be resorted to; the half-seats 53, 53 are given their desired conformation during molding by a mold part at the inner end of the mold part that forms the recess 50 and which is to be withdrawn in a direction toward the front of the structure, or upwardly as viewed in Figure 8, while the half-seats 56 and 57 are given their desired 180-degree configuration by mold parts that are separable or to be withdrawn in a direction toward the rear of the molded structure, or downwardly as viewed in Figure 8.

Breakage of the glass part 25 will be seen to be readily accomplished, the relatively small force applied at the finger-piece end 22^b of lever 22 being considerably multiplied at the anvil 31 due to the relatively short lever arm of the latter from the pivot pin 37. Once the glass part 25 is broken, those portions of the molded structure that are in front (to the left in Figure 6) of the lower or straight portion 22^a of lever 22 are protected against being subjected to detrimental strain by continued actuation of the lever, by limiting the extent of outward movement of the upper end of the lever where the actuating force is applied. Thus, as is better shown in Figure 6, the upper end of the U-shaped finger-piece lever portion 22^b passes through the slot 35 in the well wall 20^e where it has an upward extension 22^f that is directed toward the upper boss 16 through which a securing screw 14 passes. This end part 22^f extends toward the adjacent inclined face of the boss 16 from which, in normal position as shown in Figure 6, it is spaced by a short distance, and as the lever 22 is pulled in counterclockwise direction in Figure 6, the lever end 22^f engages the wall 11 after a lever movement sufficient to break the glass 25 and resists further pull of the lever so that the lower end thereof cannot exert any force against the wall 23 or other parts of the structure. This stoppage of lever movement is effected by engagement of the lever end 22^f with a part of the molded support 10 that is closely adjacent the upper securing screw 14, thus further relieving the molded structure of detrimental strains and in effect imposing them upon the anchorage of the device to the wall or other support such as the upper screw 14. The location and support of the pivot pin 37 virtually at or by the lower boss 16, and hence closely adjacent to the lower anchoring screw 14, contribute toward having the lower anchorage distribute or take up stresses of reaction at the fulcrum or pivot 37 during glass-breaking action of the lever.

Overstraining of the device is thus guarded against. Normally switch 41-42, where the signalling system is of the open circuit type, stands open as in Figure 4, being held open because the glass 25 prevents lever 22 from swinging under the bias of the spring 41; when the lever is pulled and the glass broken, spring contact 41 follows up the movement of the lever and closes the circuit at fixed contact 42. Manual release of the lever leaves the latter under the bias of spring 41, with the finger-piece part 22^b materially projected out of the well 20 to an extent permitted by the stop action of lever end 22^f. The broken glass and this outward projection of the finger-piece 22^b are visual indications that the signal station has been "pulled" in addition to the signal actuation that results from closure of the circuit at contacts 41, 42. Replacement of the broken glass restores the parts to normal positions.

It will thus be seen that there has been pro-

vided in this invention a signalling station and apparatus in which the several objects heretofore noted, together with many thoroughly practical advantages, are successfully achieved. The device is compact, neat and attractive in appearance, its fabrication by molding out of plastic materials is facilitated, and in practical use it is of reliable action. Replacement of a broken glass part is easily and readily accomplished and, moreover, selectivity of legends to be displayed is achieved in a simple and thoroughly practical manner.

As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

1. An alarm signalling station comprising a molded plastic casing-like structure having a front wall with spaced rearwardly extending reinforcing bosses between which said front wall is provided with a rearwardly depressed pocket-like portion positioned adjacent one of said bosses and being open at the front and forming a finger well and another rearwardly depressed portion adjacent the other of said bosses and forming a front seat for a frangible member, a lever extending substantially from one of said bosses to the other and in back of said second-mentioned depressed portion but traversing said first-mentioned depressed portion, the latter having opposed slots in the walls thereof for the passage therethrough of said lever so that one end of the lever terminates adjacent said first-mentioned boss, means mechanically related to said second-mentioned boss forming a pivotal support for the other end of said lever, said second depressed portion having a frangible member seated therein and having an aperture through which said lever acts upon said frangible member to break it, means holding said frangible member in the seat formed by said second depressed portion, and signal control means responsive to actuation of said lever appropriate to break said frangible member, said two spaced bosses having means for securing said casing-like structure to a supporting surface and being thereby anchored to mutually resist stresses exerted by said lever.

2. An alarm signalling station according to claim 1 in which the portion of the lever that traverses said first-mentioned depressed portion is curved forwardly of said casing-like structure to facilitate passage of a finger behind it and into said finger well.

3. An alarm signalling station according to claim 1 in which said first-mentioned end of said lever coacts with a portion of said casing-like structure at said first-mentioned anchored boss to limit outward swing of the lever.

4. An alarm signalling station according to claim 1 in which opposed walls of said first-mentioned depressed portion are forwardly divergent to facilitate molding of said slots therein.

5. An alarm signalling station according to claim 1 in which said signal control means comprises two coacting conductive switch elements respectively secured directly to said molded plastic casing-like structure by which they are insulated from each other.

6. An alarm signalling station according to claim 1 in which said signal control means comprises two coacting conductive switch elements

respectively directly secured at the rear to said molded plastic casing-like structure and thereby insulated from each other, one of said switch elements being in the form of a spring member biased toward the other switch element and having means whereby it insulatingly engages said lever and biases the latter in forward direction relative to said finger well whereby, upon breaking of said frangible member, said spring member swings said lever to project the portion that traverses said finger well in outward direction relative to the latter.

7. An alarm signalling station according to claim 1 in which said front wall is provided with integrally molded rearwardly projecting bosses spaced to either side of that portion of the lever that passes in back of said second-mentioned depressed portion, the aforesaid means for holding said frangible member in its seat comprising means engaging the frangible member at its respective ends and respectively secured to said last-mentioned spaced bosses.

8. An alarm signalling station according to claim 1 in which said front wall is provided with integrally molded rearwardly projecting bosses spaced to either side of that portion of the lever that passes in back of said second-mentioned depressed portion, said frangible member comprising a quadrangular piece of glass and the holding means therefor comprising a quadrangular open frame that overlaps said quadrangular glass only at two opposed ends of the latter, and securing means coacting respectively with said last-mentioned spaced bosses and said overlapping frame portions for securing said frame in place.

9. An alarm signalling station according to claim 1 in which said pivotal support for said lever comprises a pivot pin that extends parallel to said front wall and, molded integrally with said front wall, a plurality of complementary half-seat-forming portions spaced in the direction of the axis of said pin and molded respectively from the front side of said front wall and the rear side of said front wall.

10. In signalling apparatus, in combination, a plate-like support having a rearwardly bulging portion forming a finger well that is open toward the front and having adjacent thereto means forming a seat for receiving a frangible member at the front of said plate-like support, a frangible member in said seat and provided with means engaging said frangible member at two spaced points coacting to hold said frangible member in said seat, an actuating member having means at the rear of said front wall for movably supporting it, said actuating member having a handle portion that extends into said finger well through an aperture in a wall of said well, said actuating member having force-applying means engageable with said frangible member to break it in response to manual force applied to the handle portion of said well, and signal control means actuated upon movement of said actuating member sufficient to break said frangible member.

11. A signalling apparatus according to claim 10 in which said holding means for said frangible member comprises a part having a front face and a rear face which bear respectively different legends, together with means reversibly securing said holding means to said support to selectively position it with either of said legend-bearing faces on the outside.

12. In signalling apparatus, in combination, a wall member having rearward thereof a manual

actuator and having a rearwardly bulging portion forming a finger well that is open toward the front and having slots in two opposed side walls of said well, said manual actuator traversing said finger well to present a portion thereof to said well for manual engagement from the front of said wall member and having divergent arms extending respectively through said slots to the rear of said wall member whereby movement thereof is limited, one of said arms having an extension which has pivotal connection with said wall member at the rear of the latter, and a frangible member supported at the front of said wall member and adjacent said pivotal connection, said arm extension having force-applying means to break said frangible member.

13. In signalling apparatus, in combination, a wall member having a rearwardly bulging portion forming a finger well that is open toward the front and having slots in two opposed side walls of said well, a manual actuator having a forwardly bulging portion that traverses said finger well so that a finger may be inserted into said well and behind said bulging portion of said actuator for manually actuating the latter, said bulging actuator portion having divergent arms extending respectively through said slots to the rear of said wall member whereby movement thereof is limited, and signal control means responsive to actuation of said actuating member.

14. In signalling apparatus, in combination, a wall member having a rearwardly bulging portion forming a finger well that is open toward the front, said finger well having a slot in a wall thereof, a manual actuator comprising a finger-piece portion in said finger well for manual actuation thereof from the front of said wall member and an extension from said finger-piece portion and through said slot to the rear of said wall member whereby movement of said actuator is limited, said extension having pivotal connection with said wall member at the rear of the latter, signal switch means, and a frangible member carried by said wall member and coacting with said extension and said switch means to hold said actuator at or near one limit of its range of movement relative to said well and to hold said switch means in unactuated position.

15. In signalling apparatus, in combination, a substantially rectangular frangible member, a wall member having means forming a seat at the front thereof for said frangible member, means for holding said frangible member in said seat to facilitate breaking thereof comprising an open rectangular frame having means for securing it to said wall member, two opposed sides of said frame having a spacing not less than the width of said frangible member and the other two opposed sides of said frame having a spacing less than the length of said frangible member whereby the last-mentioned two opposed sides of the frame respectively overlap and hold two ends of said frangible member, and means for applying breaking force to said frangible member intermediate said overlapped ends thereof.

16. A signalling apparatus according to claim 15 in which the two faces of said open rectangular frame carry respectively different legends, said means for securing said frame to said wall member comprising means for detachably and reversibly securing said frame to said wall member to selectively face either of said legend-bearing faces toward the front.

17. An alarm signalling station comprising a molded plastic plate-like support having a wall

member, signal control means carried by said support comprising a member having a supporting pin therethrough with the axis of said pin parallel to said wall member, and, molded integrally with said wall member, a plurality of complementary half-seat forming portions spaced and aligned along an axis parallel to said wall member for axially receiving said pin, said complementary half-seat forming portions having their respective half-seats correspondingly spaced and aligned and facing respectively toward the front and toward the rear of said wall member for engaging and holding the pin at axially spaced front and rear portions thereof, said wall member being apertured from the front opposite such of said half-seats as face toward the front.

18. An alarm signalling station according to claim 17 provided with a frangible member having means coacting with said wall member for supporting it in a position where it is visible from the front of said wall member, said pin-supported member having a part to engage and break said frangible member, said supporting means for said frangible member covering over that portion of said wall member that is apertured opposite such of said half-seats as face toward the front.

19. In signalling apparatus, in combination, a frangible member, a wall member having means for supporting said frangible member comprising

a holding element having two faces carrying respectively different legends and means for detachably and reversibly securing said holding element to said wall member to selectively face either of said legend-bearing faces toward the front, and means for applying breaking force to said frangible member.

20. In signalling apparatus, in combination, a wall having a rearwardly bulging portion forming a finger well that is open toward the front, an actuating member positioned rearwardly of said wall member and having means for movably supporting it relative to the latter, said actuating member having a handle portion that extends into said finger well through an aperture in a wall of said well for manual actuation thereof from the front of said wall member, and signal control means responsive to actuation of said actuating member.
